Court A. Cooper,
A. G. Hammann.

UNITED STATES PATENT OFFICE.

CHARLES G. FAIRCHILD, OF OBERLIN, OHIO.

GAS-HOLDER.

SPECIFICATION forming part of Letters Patent No. 357,276, dated February 8, 1887.

Application filed January 26, 1886. Serial No. 189,834. (No model.)

To all whom it may concern:

Be it known that I, CHARLES G. FAIRCHILD, a citizen of the United States, and a resident of Oberlin, in the county of Lorain and State 5 of Ohio, have invented certain new and useful Improvements in Gas-Holders, of which the following is a specification.

My invention relates to that class of gas-holders employed for use with portable apparatus—as, for instance, with chemical apparatus used in public lectures, stereopticons, &c.; and my invention consists of a bag combined with a contractile envelope, so constructed as to increase its contractile force in proportion 15 as the bag is expanded, and to reduce its force as the area of the bag is contracted, so as to maintain a uniform pressure upon the gas within the bag, however the volume of the gas may increase or diminish.

20 In the drawings, Figure 1 is an external view of my improved gas-holder, illustrating one form of envelope. Fig. 2 is a transverse section of a holder and support, illustrating another form of contractile envelope. Fig. 3 25 is an external view of a holder, illustrating a third form of envelope. Fig. 4 is a transverse section on the line 1 2, Fig. 3. Fig. 5 is the same view as Fig. 4, showing the holder contracted.

30 The gas holder or receptacle A is preferably in the form of a cylindrical bag having rounded ends, one of which is provided with a neck, b, for connection with the supply and discharge tube d, the bag being formed of any flexible 35 material impervious to gas—as, for instance, of rubber fabric. To the bag is applied a contractile envelope, which may be formed in various ways, so that as the gas is introduced into the bag under pressure and the latter is 40 expanded the envelope will yield, but will increase its resistance to the expansion of the bag in proportion as the latter increases in size, and conversely the said contractile envelope will contract with greater force when 45 the bag is full of gas, and its contractile power will decrease in proportion as the quantity of gas in the bag is diminished. By this means a practically-uniform pressure upon the gas is secured, so that it is not necessary to use a 50 regulating apparatus and vary the latter from time to time as the gas becomes exhausted.

This uniform action results from the fact that while the contractile force of the envelope is greater when the bag is full of gas the internal area of the bag is also greatest at such time, 55 and that as the bag collapses and the contractile force of the envelope diminishes the internal area of the surface of the bag also diminishes.

One of the methods of constructing the contractile envelope is illustrated in Fig. 1, which shows the bag A as inclosed in a net consisting of crossed bands or cords of rubber, the envelope contracting to force out the gas, and also simultaneously contracting the bag, bringing 60 the sides thereof together and reducing the area of the internal surface. 65

Another means of securing a contractile envelope is illustrated in Fig. 2, which shows the bag as supported upon a grooved table or platform, D, with parallel ribs f, of wood or other suitable substance, arranged upon the outside of the bag, and with cords or bands g, each passing round a guide-roller, h, encircling the bag, and passing around another guide-roller, i, 70 adjacent to the roller h, and each connected to a spring, j.

When the bag is contracted to the dimensions illustrated in dotted lines, Fig. 2, the springs j are also contracted and exert but little force, and as the bag expands and widens the loops of cord or bands composing the same the springs j are distended and their resistance increases. When the bag is being exhausted, the power of the springs j decreases 80 in proportion as the dimensions of the bag are contracted by the contraction of the encircling loops.

A preferable construction of the envelope is shown in Figs. 3, 4, and 5, in which rubber 90 bands m are used to encircle the bag and the ribs f applied thereto, the expansion of the bag being accompanied by a constantly increased resistance of the bands, and the dimensions of the bag decreasing as the bands become weakened. This construction is attended 95 with a great advantage, resulting from the ease with which the compressive power of the gas-holder may be increased or diminished by adding to or reducing the number of bands applied to the holder.

The above-described gas-holder may be used

for any of the purposes for which gas-holders are ordinarily employed—as, for instance, in laboratories, for stereopticons, public chemical experiments, and other purposes.

5 I do not claim, broadly, a bag inclosed by isolated elastic bands, my invention being distinguished from such an arrangement by the use of an envelope which presses on all sides of the bag to expel the contents with the same effect as when a flat weighted board is used. Without limiting myself to the precise construction and arrangement of parts shown, I claim—

1. The combination of a flexible bag and an envelope of elastic material inclosing the bag throughout its length capable of yielding as the

bag is expanded, and of affording an increased resistance in accordance with the expansion of the bag, substantially as described.

2. The combination of a cylindrical flexible bag, a series of longitudinal strips, and a contractile band around the strips constituting a contractile envelope inclosing the bag throughout its length, substantially as described.

In testimony whereof I have signed my name to this specification in the presence of two subscribing witnesses.

CHARLES G. FAIRCHILD.
